UNITED STATES PATENT OFFICE.

HARRY M. MOSES, OF CHICAGO, ILLINOIS, ASSIGNOR, BY MESNE ASSIGNMENTS, TO THE STEINAU COMPANY, A PARTNERSHIP CONSISTING OF LESLIE S. STEINAU AND NORVIN J. STEINAU, OF LOUISVILLE, KENTUCKY.

EASEL.

Application filed August 20, 1927. Serial No. 214,336.

This invention relates to easels, and more particularly to a plate adapted to be applied to backs of signs, show-cards, pictures and the like, for the purpose of supporting the same in upright or inclined position in windows and on counters or tables.

The purpose of the invention is to provide an easel-like support which is capable of ready and secure attachment to the back of a display or other self-supporting sign and possessing other advantages such as cheapness in manufacture and the capacity to lie flat against the back of the sign during shipment.

15 A preferred embodiment of the invention is disclosed in the accompanying drawing in which

Figure 1 is a perspective view of a sign showing the easel attached to the back thereof.

Figure 2 is a view in cross-section as taken on line 2—2 of Figure 1.

Figure 3 is a perspective view of the easel plate prior to attachment to a sign.

25 The sign A herein disclosed is typical of the character of display cards or signs equipped with easels, the same being preferably made of relatively thick cardboard or a stiff composition board. The easel B consists of a metal plate stamped in one operation from a suitable grade of thin metal. In the preferred form of easel, the plate is rectangular in shape, its length being substantially equal to the width or 30 vertical dimension of the sign. Extending lengthwise of the plate is a central tongue 1 formed by cutting or punching a U-shaped kerf 2 directed toward one end of the plate, with its unsevered side spaced from the adjacent end edge to form a top marginal band 3. The tongue 1 is also surrounded on its three severed sides by two side strips 4 and a bottom strip 5 forming a U-shaped member which serves as the leg or brace when 35 the easel is in supporting position. Along the top marginal strip are two transverse rows of prongs 6, these being triangularly shaped bits of the metal which are punched out of the plate and bent at right angles to the back of the plate, the prongs being formed in the same punching operation which cuts out the central tongue. A series 40 of similar prongs 7 are likewise formed in the central tongue, these prongs being dis-

tributed throughout the entire area of the tongue in any suitable arrangement, and the number being determined by the dimensions. The prongs are relatively short, not over $\frac{1}{8}$ of an inch and have sharp points.

The easel plates are applied to the back 60 of the signs in any suitable manner, preferably by feeding the signs to a punch press, although any pressure applying means can be used for driving the prongs into the back of the sign, the same being of a material 65 soft enough to allow the prongs to sink in without bending, but of ample toughness to hold them fast. The easels having been applied, it is only necessary for the user to 70 bend the free portion of the plate outwardly to the desired angle to the back to form the supporting brace for the sign.

The merit of the easel plates herein disclosed resides in the simplicity of construction and the ease with which they may be 75 applied, and further, in the fact that when initially applied they lie flatwise against the sign without projections such as screw heads, hinges and like parts found in the usual forms of metal or cardboard easels 80 commonly employed for this purpose.

This feature is a particularly important one from the standpoint of the manufacture as it makes for ease and economy in shipment, inasmuch as the signs can be packed 85 flat thus occupying less space and requiring less care in separating the signs to prevent marring of the faces. Furthermore, the prongs provide a permanent fastening for the easels much more so than glue or other 90 adhesive and far less expensive to apply than glue, screws or other fastening means. And finally, the plates being of one piece metal, there are no parts that can break or become displaced in shipment or during the 95 life of the sign.

Manifestly the precise form of the plate may be altered without sacrificing its advantageous features. For instance, the central tongue 2 may form the brace and thus 100 bend outwardly, in which case the prongs would be formed in the surrounding strips—the reverse of the form disclosed. Again, it would be practical to omit the central tongue entirely, although its presence is desirable since it prevents the upper 105 rows of prongs 6 from being loosened in the act of bending the free portion outwardly.

into supporting position. And finally, the shape and proportions of the plate may be varied for different sizes of signs, since generally speaking the length of the supporting leg must increase with the height of the sign. For these reasons, I do not wish to be limited to the specific form of device herein disclosed:

I claim as my invention:

- 10 An easel for a display panel or the like, comprising a metal plate having a centrally disposed tongue connected to the surround-

ing portion of the plate adjacent one edge portion, and having a plurality of relatively small prongs struck from the plate throughout said tongue and edge portion, said plate being adapted to be applied to one face of said panel by pressing the prong side thereof flush with the surface of said panel and bending the free portion thereof outwardly 20 to form a supporting leg.

Signed at Chicago, Ill. this 17th day of August, 1927.

HARRY M. MOSES.
